UNITED STATES PATENT OFFICE.

JOHN F. HUTT, OF HARTFORD, WISCONSIN.

HAT-RACK.

1,116,706.

Specification of Letters Patent. Patented Nov. 10, 1914.

Application filed April 24, 1912. Serial No. 692,805.

To all whom it may concern:

Be it known that I, JOHN FLINN HUTT, a citizen of the United States, and resident of Hartford, in the county of Washington 5 and State of Wisconsin, have invented certain new and useful Improvements in Hat-Racks; and I do hereby declare that the following is a full, clear, and exact description thereof.

10 My invention has for its object to provide a simple, economical and efficient hat rack, the construction and arrangement being such that the hat is inserted therein and securely held in place by a rim-clip, the 15 rack being formed from a single piece of bent wire of any desired gage capable of sustaining the load to which it is applied.

With the above object in view the invention consists in certain peculiarities of construction and combination of parts as set 20 forth hereinafter with reference to the accompanying drawings and subsequently claimed.

In the drawings Figure 1 represents a 25 perspective view of a hanger embodying the features of my invention, and Fig. 2, a face view of the same upon a reduced scale illustrating a hat suspended within the hanger.

Referring by characters to the drawings 30 1 represents a centrally disposed suspension loop having its cross ends merged into supporting arms comprising opposite diverging sections 2, which sections are intersected by parallel vertical sections 2', the 35 said supporting arms being adapted to rest flatly against a wall or other fixture and is held in suspension by a pin or other suitable member.

The lower ends of the arms are outwardly 40 bent and thereafter merged into upwardly inclined rim-clips 3, the rim-clips being alined with the straight sections 2' of the arms to form in conjunction therewith jaws for the reception of a hat-rim. The upper 45 ends of the rim-clips 3 are cross-connected by a downwardly bowed wire stretch constituting a crown rest 4 for the support of a hat crown which, as best shown in Fig. 2, is nested thereon. After the wire is thus 50 formed, the ends thereof are joined together and connected by solder or other suitable means, this connection as shown being effected in one of the oblique stretches 2'

that form part of the supporting arm. It should be understood however that the abutting joint of the wire ends may be made at any other point of the device without departing from the spirit of my invention. 55

It will be readily understood from the foregoing description that a hat can be 60 simply dropped into position upon the hanger and its rim will rest within the jaws formed between the vertical stretches 2' and the rim clips 3, the crown of the hat being engaged by the bowed rest 4. It is 65 also understood that the hanger can be efficiently utilized for the support of straw, stiff or soft hats and that when the same are positioned upon the hanger there is no liability of their being inadvertently displaced as in the case of an ordinary hook, and while I have shown and described the 70 sections 2 of the arm as being obliquely disposed it is apparent that any suitable scroll form may be substituted for that shown, 75 the essential elements being the bowed crown-rest and rim-clip.

I claim:

As a new article of manufacture, a hat 80 rack comprising a single strand of wire twisted to form a centrally disposed suspension loop, the ends of which are merged into supporting arms having oppositely diverging downwardly extended sections that are merged into vertical parallel sections, 85 the lower ends of the parallel sections being bent upon themselves and extended upwardly in alinement with said parallel sections to form flared looped rim-clips whereby hats of varied sized rims may be 90 seated therein, the rims of which are adapted to extend beyond the rim clips, and a concavo-convex cross-connection between the rim clips comprising a crown rest that is adapted to approximately conform to the contour of the crown of a hat seated therein.

In testimony that I claim the foregoing I have hereunto set my hand at Hartford in the county of Washington and State of 100 Wisconsin in the presence of two witnesses.

JOHN F. HUTT.
